that *Leucostoma* represents a high order of organization and is the most advanced of the *Leucostomidae*. The genus *Leucostoma* is divided into two subgenera, *Leucostoma* and *Leucostoma* (Leucostoma), and the latter is divided into two subgenera, *Leucostoma* and *Leucostoma* (Leucostoma).

UNITED STATES PATENT OFFICE

2,515,849

SPRING CLAMP

Samuel J. Baril, Brooklyn, N. Y., assignor to The Hobart Co., Inc., New York, N. Y., a corporation of New York

Application June 26, 1947, Serial No. 757,132

2 Claims. (Cl. 24—137)

1

The present invention relates to spring clamps and, more particularly, to the type of such clamp commonly referred to as a "spring clothespin"; and has for a general object the provision of such a clamp which, as is usual, is characterized by a spring device including a helical spring portion located in opposed cooperating transverse notches in the jaw elements, with the provision therein of simple but effective means for preventing any substantially lateral movement of either jaw element relative to that helical spring portion, i. e., longitudinal movement of the latter with respect to the jaw elements, so as effectively to eliminate a rather common tendency for the jaw elements to slide laterally with respect to that helical spring portion and each other and, as a consequence, to become disassembled.

A more specific object of the invention is to provide in the opposed cooperating transverse notches in the jaw elements of such a spring clamp suitable projecting means to intervening turns of the helical spring portion of the spring device which holds the jaw elements together and biases them toward each other, so as effectively to minimize lateral movement of the jaw elements with respect to that helical spring portion and to each other.

Another object of the present invention is to provide such means for preventing relative lateral movement of the parts of such a spring clamp in the nature of a plurality of ridges on the curved surfaces of the opposed cooperating transverse notches in the jaw elements so as to form together grooves in which successive turns of the helical spring portion may be received and securely seated to prevent relative lateral movement of parts.

A further object of the present invention is to provide a structural embodiment of the device which is readily constructed and permits efficient use and operation thereof.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had to the following detailed description taken in connection with the accompanying drawing, in which:

Fig. 1 is an edge view of an embodiment of the spring clamp of the present invention;

Fig. 2 is a side view of the structure shown in Fig. 1;

Fig. 3 is a plan view of the inner face of one of the jaw elements of the structure shown in Figs. 1 and 2; and

Fig. 4 is an enlarged sectional view taken on line 4-4 of Fig. 2.

10 Referring to the drawing like numerals identify similar parts throughout and, as will be seen therefrom, an embodiment of the present invention may comprise a pair of jaw elements 10, 10 which are of similar construction. Each jaw 15 element 10 includes a mid portion 11 having in the inside face thereof a transversely extending semi-circular groove 12 located substantially intermediate of its two ends with one end 13 providing a compressible handle or grasp and the 20 other end 14 providing a clamping nose. As is usual, each jaw element 10 is provided with a transversely extending groove 15 in its outer face between its mid portion 11 and its clamping nose 14.

25 The two jaw elements 10, 10 are pivoted together with their clamping noses 14, 14 biased to engagement with each other by a spring device 16 which includes a transversely extending, helical portion 17 made up of a relatively large number of successively arranged, circular turns and terminating at each end in similar spring arm structures 18, 18. As shown in Figs. 1 and 2, each spring arm structure 18 is extended forward along the edges of the two jaw elements 10, 10, and has its end 19 turned inwardly to lie transversely in one of the grooves 15 in the outer face of one of the jaw elements. With the parts assembled, as shown in Figs. 1 and 2, the spring device 16 effectively pivots together the two jaw elements 10, 10 with their clamping noses 14, 14 biased to engagement with each other.

In order to avoid any tendency for either of the jaw elements 10, 10 becoming askew with respect to the other jaw element, with a possible resultant tendency for disengagement of one of the turned ends 19 of spring side arm 18 moving laterally out of its seating groove 15, the present invention concerns itself with keeping those two jaw elements substantially aligned, as indicated in Figs. 1 and 4, with a retention therebetween in proper position of the helical portion 11 of the spring device. This is preferably accomplished by providing each semi-circular, transversely extending notch 12 with a plurality of longitudinally extending ridges 20-20 which

cooperate to provide therebetween a plurality of longitudinally extending grooves 21-21. Such ribs and intervening grooves are most conveniently formed when the jaw elements 10, 10 are molded from suitable plastic material, but of course, they can be formed by cutting grooves in the older, more common type of spring clamp jaw elements which are formed of wood.

As is more particularly shown in Fig. 4, the plurality of longitudinally extending ribs or ridges 20-20 and intervening grooves 21-21 provide suitable means to intervene successive turns of the helical spring portion 17 so as to prevent or minimize longitudinal movement of the latter with respect to jaw elements 10, 10. The turns of the helical spring portion 17 seat in the grooves 21-21 with the ribs or ridges 20-20 interdigitating those successive turns. Of course, it will be understood that the number of grooves 21-21 provided by the ridges or ribs 20-20 need not, for the purposes of the present invention, substantially equal the number of turns in the helical spring portion 17, although such arrangement as that proposed in Fig. 4 is preferred. For example, with the jaw element structures proposed in the drawing, a spring device which has a helical portion consisting of, for example, only three or four turns will assure cooperative functioning of that ridge and groove construction in minimizing longitudinal movement of the latter with respect to jaw elements 10, 10. This is true, since with a spring device of that type wherein only a few helical turns are provided, those turns will, at one or more points, engage in certain of the grooves, particularly if the width of the grooves are at least substantially equal to the diameter of the spring wire from which the spring device is formed. It will be further understood that the desired results may be obtained in a construction where the ridges or ribs 20-20 do not extend substantially normal to the axis of the notch or groove 12, such as diagonally or obliquely with respect thereto, and, of course those ridges or ribs need not extend completely across the curved surface of each spring-receptive notch 12; and that various modified forms of that structure which might be employed to advantage in obtaining the desired end will readily occur to one skilled in the art.

It will thus be seen that the objects set forth above, including those made apparent from the

preceding description are efficiently attained and, since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. In a spring clamp of the type characterized by a pair of rigid jaw elements pivoted together by a spring device including a portion located in opposed cooperating transverse notches in the jaw elements, the feature comprising, in combination, an elongated helical spring portion disposed in the opposed notches of the jaw elements, and a plurality of ridges formed on the walls of the notches arranged substantially transversely of the notches to intervene turns of the helical spring portion to minimize longitudinal movement of the latter with respect to said jaw elements.

2. In a spring clamp of the type characterized by a pair of rigid jaw elements pivoted together by a spring device including a portion located in opposed cooperating transverse notches in the jaw elements, the feature comprising, in combination, an elongated helical spring portion of a certain number of relatively adjacent successive turns disposed in the opposed notches of the jaw elements, and a plurality of substantially parallel ridges formed on the walls of the notches to define therebetween a plurality of adjacent grooves extending across the notches generally normal to the axis of the helical spring portion with the successive turns of the latter located in the grooves to minimize longitudinal movement of the helical spring portion with respect to said jaw elements.
